UNITED STATES PATENT OFFICE.

JOHN M. BURTON, OF WICHITA, KANSAS, ASSIGNOR, BY MESNE ASSIGNMENTS, TO HIMSELF, AND GEORGE D. BURTON, OF BOSTON, MASSACHUSETTS.

CAR-COUPING.

SPECIFICATION forming part of Letters Patent No. 476,784, dated June 14, 1892.

Application filed February 14, 1891. Serial No. 381,492. (No model.)

To all whom it may concern:

Be it known that I, JOHN M. BURTON, a citizen of the United States of America, residing at Wichita, in the county of Sedgwick and State of Kansas, have invented certain new and useful Improvements in Car-Couplers, of which the following is a specification, reference being therein had to the accompanying drawings, and the letters of reference thereon, forming a part of this specification.

The object of this invention is to provide a car-coupling that is equally suitable for freight or passenger service, that is adapted to be coupled to a like coupling, to the ordinary link-and-pin coupling, or to any of the standard twin-jaw couplings—such, for instance, as those of the Janney and Miller type—and that shall be cheap and durable in construction and simple in operation.

Figure 1 represents a top plan view showing this improved coupling coupled with a pointed hooked coupling of an ordinary and well-known type. Fig. 2 represents a similar view showing the coupling coupled with a coupling of the Janney or Miller type. Fig. 3 represents a side elevation showing the coupling coupled with an ordinary link-and-pin coupling. Fig. 4 represents a perspective view of the coupling, showing the swinging point thrown to one side; and Fig. 5 represents a horizontal section showing the point locked in position in front of the hooked draw-head.

Referring to the drawings, the letter A indicates the draw-bar, which is provided at its forward end with a hook-shaped draw-head *a*, the hooked portion being indicated by *d*. The front end of the hooked draw-head *a* is recessed, as at *R*, and provided with a pin-hole passing vertically through the recessed portion of the draw-head and adapted to receive a pin *P*, for the purposes hereinafter described. In practice the hooked draw-head *a* is formed integral with the draw-bar *D*. The draw-head at the side opposite to the hooked portion *d* and slightly in rear thereof is provided with two perforated ears *d' d'*. The swinging point *a'* is provided with an oppositely-beveled front portion and at its rear with a vertically-perforated shank *d''*, which is embraced by the ears *d' d'* and pivotally secured therein by

means of a pin or pins *C C*, the rear face of said point being of the proper shape to coincide with the front end of the draw-head *a* and provided with a rearwardly-projecting lug *P'*, adapted to enter the recess *R* of said draw-head and provided with a perforation *e*, which registers with the pin-hole in the draw-head when the point is in the position shown in Figs. 1 and 5, and is locked therein by means of the pin *P*. The shank *d''* of the point *a'* is flattened upon opposite sides, as at *v v'*, (see Figs. 4 and 5,) which flattened sides are adapted to be engaged by the free end of a flat leaf-spring *s*, pivoted to the side of the draw-bar, which is provided with an elongated recess *m*, which receives the end of said spring when it is pressed back by the shank *d''*. When the point *a'* is swung to its position in front of the draw-head or to the side thereof, the free end of said spring will bear against one of the flattened sides of the shank *d''* and serve to hold said point in place and prevent any oscillation or rattling of the same. The said shank may, if desired, be flattened only upon one side, as *v*, for when the point has been swung to the position shown in Figs. 1 and 5 and locked by the pins *P* the point *a'* will then be firmly locked in position.

The operation of my coupling will be readily understood from the foregoing description. In Fig. 1 I have shown it coupled with an ordinary form of hooked coupling. When used with this form of coupling, the point *a'* is swung around in front of the forward end of the draw-head *a* and locked, as described. The two pointed portions of the hook-couplings coming in contact yield until the two hooks overlap, when they automatically couple in the ordinary well-known manner.

In Fig. 2 I have shown my coupling coupled with the well-known coupling of the Janney or Miller type, and wherein the dotted lines represent the position in which the pivoted locking-hooks are set before bringing the couplings together. The point *a'* of the coupling is first swung back to the side of the draw-bar, as shown in Figs. 2 and 4, where it is held by the spring *s*, as before described, and the two couplings brought together, when the hooked portion *d* of the draw-head *a* engages the inner pivoted locking-hook and forces it back

into a recess of its draw-head, and at the same time causes the other pivoted locking-hook to engage the rear face of the hooked portion of the draw-head *a*, as shown by full line in Fig. 5 2, in the ordinary and well-known manner.

When it is desired to couple my coupling with the ordinary link-and-pin coupling, the point *a'* is swung to one side of the draw-bar, as before described, and the link caused to 10 enter the recess *R*, wherein it is locked by the pin *P*, as clearly shown in Fig. 3.

It will be obvious that where two couplings constructed according to my invention are to be coupled together the points *a'* will be swung 15 in front of the draw-head *a* and locked by the pins *P* and coupled together in like manner to the coupling shown in Fig. 1. It will also be obvious that should it be desired to couple my improved coupling with a hooked coupling 20 in which the hooks occur upon the same side the coupling may be reversed or turned over, so as to bring the hooks in the proper position for effecting the coupling.

I claim—

25 1. In a car-coupling, the combination of the draw-bar provided with a hooked draw-head, a swinging point pivoted to said draw-head and adapted to be swung in front thereof to form a pointed hooked coupling or to one side thereof to permit the coupling of said draw-head with a twin-jaw coupling, and means for holding said swinging point in either position, substantially as described.

2. In a car-coupling, the combination of the 30 draw-bar provided with a hooked draw-head recessed in its front end and having a pin-hole and pin, and a swinging point pivoted to

said draw-head and adapted to be swung in front thereof to form a pointed hooked coupling or to one side thereof to permit the coupling of said draw-head with a link, substantially as described. 40

3. In a car-coupling, the combination of a draw-bar, a hooked draw-head provided with a recess in its front end and a vertical pin 45 passing through said recess, perforated lugs opposite the hooked portion of the draw-head, a swinging point provided with a vertically-arranged and flattened shank pivotally secured between said lugs and a perforated lug 50 adapted to enter the recess in the draw-head and be held therein by the said pin, and the flat spring for yieldingly holding the point when turned in either position, substantially as described. 55

4. In a car-coupling, the combination of the draw-bar, the draw-head, the pivoted swinging point provided with the vertically-pivoted shank flattened at its sides, and the flat spring fixed to the draw-bar and yieldingly bearing 60 against said pivoted shank, substantially as described.

5. In a car-coupling, the combination of the draw-bar, the draw-head provided at its front end with a recess and the vertical pin-hole, 65 and the pivoted swinging point provided with the perforated lug adapted to enter said recess and be secured therein by means of a pin, substantially as described.

JOHN M. BURTON.
